(57) **CLAIM**

The ornamental design for a bottle, as shown and described.

DESCRIPTION

FIG. 1 is a front perspective view of an embodiment of a bottle in accordance with our new design;

FIG. 2 is a front elevational view of the bottle shown in FIG. 1;

FIG. 3 is a rear elevational view of the bottle shown in FIG. 1;

FIG. 4 is a right-side elevational view of the bottle shown in FIG. 1;

FIG. 5 is a left-side elevational view of the bottle shown in FIG. 1;

FIG. 6 is a top plan view of the bottle shown in FIG. 1;

FIG. 7 is a bottom plan view of the bottle shown in FIG. 1;

FIG. 8 is a front perspective view of another embodiment of a bottle in accordance with our new design;

FIG. 9 is a front elevational view of the bottle shown in FIG. 8;

FIG. 10 is a rear elevational view of the bottle shown in FIG. 8;

FIG. 11 is a right-side elevational view of the bottle shown in FIG. 8;

FIG. 12 is a left-side elevational view of the bottle shown in FIG. 8;

FIG. 13 is a top plan view of the bottle shown in FIG. 8; and,

FIG. 14 is a bottom plan view of the bottle shown in FIG. 8.

The dot-dash-dot broken lines illustrates the boundary of the claim. All other broken lines depict portions of the bottle that form no part of the claimed design.

1 Claim, 12 Drawing Sheets
